UNITED STATES PATENT OFFICE

JOHN VAN BRUNT, OF FLUSHING, NEW YORK, ASSIGNOR TO INTERNATIONAL COMBUSTION ENGINEERING CORPORATION, A CORPORATION OF DELAWARE

BOILER FURNACE

Application filed November 3, 1925. Serial No. 66,437.

This invention relates to boiler furnaces and particularly such as are intended to burn finely divided fuel, as for example, pulverized coal.

5 One of the primary objects of the invention is to provide a boiler furnace which is compact and simple in construction and in which a large quantity of steam can be evaporated with an amount of evaporating area 10 considerably less than now required to produce the same quantity of steam.

Another object of the invention has to do with the provision of improvements in the connection of various portions of the boiler.

15 Further objects of the invention will appear in connection with the accompanying description of the best form of my invention now known to me, when taken in connection with the accompanying drawings, wherein

20 Fig. 1 is a cross section thru a boiler furnace embodying my improvements,

Fig. 2 is a portion vertical section and end elevation of the boiler furnace of Fig. 1, and

25 Fig. 3 is a fragmentary plan section taken on the line 3—3 of Fig. 1.

Referring now to the drawings, the reference character A denotes the combustion space of the boiler furnace, this combustion space being primarily defined by evaporating elements. The two side walls of the combustion chamber are provided with water walls B composed of a plurality of vertically extending tubes and the front wall is in part formed by such a water wall C. The roof of

30 the furnace is also composed in part by a similar water wall D, and a water screen E defines the lower portion of the combustion space of the furnace. The rear of the combustion space is defined by the banks of

40 tubes F.

The tubes 7 in part constituting the water wall C lead downwardly from the header 8—which is located somewhat below the center line of the upper main drum 9 of the boiler—45 to the header 10. The tubes 11, in part constituting the water wall D, lead from the drum 9, somewhat downwardly, to the header 8. The tubes of the water screen E lead, somewhat upwardly, from the header 10 to

50 the lower drum 12 of the boiler.

A relatively light sheathing 13 is carried on the tubes 11 of the water wall D, and beneath the water screen E is the ash pit G, which is adapted to receive the refuse particles precipitating out of the fuel and flame stream and passing thru the screen E, which screen serves the function, among other things, of cooling such precipitating ash below slag forming temperature.

The tubes 14, of which the side water walls

55 B are in part formed, extend straight up thru the roof for connection into headers 15 and the lower ends of such tubes 14 are bent so as to pass outwardly for connection into the headers 16. The headers 16, which incline upwardly from front to rear, are connected to the drum 12 by a plurality of pipes 17, each of which is somewhat bent. These connections 17 take off from the header 16 at a plurality of spaced points lengthwise thereof. A

60 plurality of connections 18 lead from the headers 15 to the drum 9, such connections also taking off from the headers at a plurality of spaced points. The headers 15 are suspended from the structural work 19 by means

65 of suspension rods 20 and the steam drum 21—which is connected to the drum 9—is also suspended. The tubes of the front wall C are suspended from the header 8, which header is in turn suspended by means of the

70 suspension rods 22 (see Fig. 2). The header 8 being suspended and the drum 9 being fixed, these two serve to support the roof and its

75 water wall.

The tubes in the side water walls, the front

80 water wall and the top water wall are provided with longitudinally extending fins 23, which fins are preferably welded to the tubes, the tubes and the fins co-operating to constitute the water wall. The fins on the tubes

85 of the front water wall are interrupted at points to provide air inlet openings 24 leading from the channels 25 formed by such water wall, the sheathing 26 and the divisions

90 27. Air enters each of the horizontal compartments 25 thru the damper controlled inlets 28. (See Figs. 1 and 3). And in traversing the space within the front wall, the

95 air becomes heated.

The front row, the middle row of tubes and

100

the rear row of tubes, of the bank of tubes F, are similarly provided with fins 29 arranged to act as baffles for baffling the products of combustion thru such bank of tubes.

5 The pulverized coal is admitted downwardly thru the burners, preferably with part of the air required for combustion, the balance being supplied thru the front wall as above described. I prefer to so admit the air and 10 the coal that violent mixture and turbulent combustion takes place within the combustion space defined by the tubes, combustion being completed before the passes of the vertical bank of tubes are reached. This turbulent 15 combustion with its comparatively intense temperature is preferred for the reason that the combustion space is defined on six sides by tubes subjected to radiant heat. These tubes, therefore, absorb heat at very high 20 rate, so high in fact that in the absence of turbulent combustion with its concomitant high temperature, the temperature within the combustion space would be so lowered that smoking, inefficiency and other draw-backs 25 would result. At the same time, by virtue of the high rate of absorption of the tubes, the boiler can be cut down in size, as can the combustion space by virtue of the turbulent combustion and short flame, whereby the 30 size of the boiler and the size of the combustion space is but a small fraction of the size required to produce the same amount of steam according to standard practice. This also means that the drums 9 and 12 can be located closer together. Thus the ground area 35 and the vertical height occupied is very materially reduced, added to which the arrangement of the various elements or units constituting the boiler furnace is much simplified.

40 What I claim is:

1. In a boiler of the radiant heat type defining its own combustion space, the combination of an upper and a lower drum at the rear of the boiler, a bank comprising a multiplicity 45 of tubes connecting said drums, side water walls in advance of said bank and each comprising a row of upright tubes having headers at their upper and lower ends, a front water wall comprising a row of upright tubes 50 having headers at their upper and lower ends, a roof water wall comprising a row of tubes connected at one end to the upper drum and at the other end to the upper header of the front water wall, a row of spaced tubes 55 defining the bottom of the combustion space connected at one end to the lower drum and at the other end to the lower header of the front water wall, enclosing sheathing for the boiler providing an ash pit and an offtake, 60 the headers for the side and front walls being exterior of said sheathing, structural work, and means whereby said upper headers are suspended therefrom, together with means 65 for admitting fuel to be burned in space in the combustion space defined by the boiler.

2. In a boiler of the radiant heat type defining its own combustion space, the combination of an upper and a lower drum at the rear of the boiler, a bank comprising a multiplicity of tubes connecting said drums, side 70 water walls in advance of said bank and each comprising a row of upright tubes having headers at their upper and lower ends, a front water wall comprising a row of upright tubes having headers at their upper and lower ends, a roof water wall comprising a row of tubes connected at one end to the upper drum and at the other end to the upper header of the front water wall, enclosing 75 sheathing for the boiler including a roof shell carried on the roof water wall, structural work, and means for suspending the front and side walls from said structural work.

In testimony whereof, I have hereunto signed my name.

JOHN VAN BRUNT.
